UNITED STATES PATENT OFFICE.

ARTURO CRISCI, OF NEW YORK, N. Y.

BOTTLE STOPPER.

Application filed October 4, 1920. Serial No. 414,654.

To all whom it may concern:

Be it known that I, ARTURO CRISCI, a citizen of the United States, and a resident of the city of New York, in the county of New York and State of New York, have invented certain new and useful Improvements in Bottle Stoppers, of which the following is a specification.

The present invention relates to improvements in bottle-stoppers, and has for its main object to provide a simple device of this type, adapted for use with bottles in which it is necessary to dispense the contents thereof in small quantities and at frequent intervals.

Another object of the invention is to provide a bottle-stopper of the character described that can be conveniently mounted upon bottles of any desired type without necessitating changes in the construction of the latter.

With these and other objects in view, which will more fully appear as the nature of the invention is better understood, the same consists in the combination, arrangement and construction of parts hereinafter described, pointed out in the appended claim and illustrated in the accompanying drawings, it being understood that many changes may be made in the size and proportion of the several parts and details of construction within the scope of the appended claims, without departing from the spirit or sacrificing any of the advantages of the invention.

Two of the many possible embodiments of the invention are illustrated in the accompanying drawings, in which:—

Figure 1 is a central longitudinal section taken through a bottle-stopper constructed in accordance with the present invention, the stopper being shown enlarged to clearly disclose the elements thereof; Fig. 2 is a section taken on line 2—2 of Fig. 1; Fig. 3 is a section taken on line 3—3 of Fig. 1; Fig. 4 is a section similar to the one shown in Fig. 1 of a modification of the invention; and Fig. 5 is a section taken on line 5—5 of Fig. 4.

Referring now first to Figs. 1 to 3, inclusive, of the drawings, the numeral 10 indicates a bottle neck, provided with a shoulder 11 around its mouth. Upon the upper end or mouth of the neck is disposed a gasket 12 of cork or similar material, and on this gasket rests centrally an upwardly extending sleeve 13, the lower end of which is

made in the form of a plate member 14, that extends across the gasket nearly into contact with the flange 15 of a stopper housing 16. The upper end of the sleeve is shaped to 60 form a seat 17 for a ball-valve 18, made of any suitable material. The sleeve 13 is disposed within a tubular valve casing 19, the latter being closed at its upper end by a perforated head 20, while its lower end terminates in a disk 21, that bears against the plate member 14. The stopper housing 16 includes a tubular portion 22, drawn over the tubular valve casing 19 and snugly fitting the same. The flange 15 of the said 70 housing is in engagement with the shoulder 11 of the bottle neck, thereby holding the elements of the stopper in position upon the bottle.

Above the valve seat, the tubular valve 75 casing is provided with openings 23, from which lead longitudinal grooves 24 on the outer face of the valve casing up to its head 20.

The stopper housing 16 is provided upon 80 its tubular portion 22 with exterior screw-threads 25, meshing with interior screw-threads of a cap 26.

In use, the cap 26 is removed by unscrewing the same and the bottle inverted, whereby the ball-valve 18 is unseated and the contents of the bottle are adapted to flow through the openings 23 and grooves 24 in the valve casing, finally escaping through the open mouth of the stopper housing 16. 90 When the bottle is brought back to its upright position, the valve 18 is automatically seated, closing access to the interior of the bottle and thus preventing impurities, etc., from entering the same. The head 20 of 95 the valve casing 19 is perforated to permit of escape of air when the valve 18 is unseated.

It will be observed that all of the elements of the stopper are disposed outside 100 of the bottle and can be conveniently assembled before being put in place thereon. Attention is also called to the fact that the stopper housing 16 not only serves as the means for holding the stopper in position 105 upon the bottle neck, but also to keep the elements of the stopper in their proper relative positions.

A modification of the invention is illustrated in Figs. 4 and 5 of the drawings, differing from the one above described in that it is considerably simplified. In this in-

stance a disk 27, provided with a central opening 28, is placed upon the bottle mouth. In the upper face of this disk is formed a recess 29, which is considerably larger than the opening 28. Into the edges of the recess are cut notches 30, for a purpose hereinafter to be described. Into the opening 28 is fitted a conically shaped cup member 31, having a flange 31' around its upper edge, said flange being disposed within the recess 29 and provided with notches 32. The disk 27 is kept in place by a stopper body 32', including a spout 33 and a flange 34, the latter being in engagement with the shoulder 11 upon the bottle neck. To the cup member 31 is fastened, at its apex, a cup 35, inverted in relation to the cup member 31.

When the bottle is in its upright position, 20 the cup member 31, acts as a valve, closing the opening 28 in the disk 27. By inverting the bottle, the said valve is unseated, permitting liquid to flow through the opening 28, notches 32, and notches 30 into the

spout 33, leaving the bottle through the latter. The valve is automatically seated, when the bottle is brought again to its upright position. When inverting the bottle, some of the liquid lodges within the cup-shaped member 35 and thereby aids in unseating the valve 31.

What I claim is:—

A bottle-stopper, comprising a tubular valve chamber closed at its upper end by a perforated head and having intermediate its ends ports from which lead longitudinal grooves upon the outer face of said chamber to its head, a sleeve fitted into said valve chamber provided below said ports with a seat, a ball-valve co-operating with said seat disposed within said valve chamber, and a stopper housing including a spout section drawn over said valve chamber and snugly fitting the same.

Signed at New York, in the county of 45 New York and State of New York, this 12th day of July A. D. 1920.

ARTURO CRISCI.
